WRINGER

Charles W. Williams, Cleveland, Ohio, assignor to
Automatic Safety Wringer Company, a partnership

Application May 19, 1937, Serial No. 143,521

24 Claims. (Cl. 68—253)

This invention relates to a clothes wringer designed from the standpoint of affording safety to the operator as well as from the standpoint of efficiently wringing clothes or any other suitable object passed therethrough.

The wringer is of the multiple roll type in which two rolls are used to effect a wringing action and the third roll provides an intake bite which guards the operator by preventing passage of the hand into the dangerous pressure roll bite. Mechanism is provided in my improved wringer to stop the operation of the same when material exceeding a predetermined thickness is fed to the intake bite. In this manner if the operator's hand should be caught in the pressure roll bite and drawn into the wringer the thickness of the hand will act to stop the operation of the device.

I prefer to employ three rolls in my improved wringer, locating them in such manner that the top roll contacts both of the other rolls. Pressure is interchangeably applied to the bite formed by the top roll and either of the other rolls desired. In each case the third roll then acts with the top or common roll to provide the intake bite.

In general the objects of my invention may be said to embody the construction of a multiple roll wringer which wrings clothes efficiently, affords adequate protection to the operator and is simple in construction. Other objects of my invention will become apparent from the description following when read in conjunction with the drawings appended hereto. The important features of my invention are summarized in the claims.

In the annexed drawings:

Fig. 1 is a front elevation showing the general construction of my wringer;

Fig. 2 is a downward view showing the wringer with the parts exposed by opening the top;

Fig. 3 is a vertical section through the wringer;

Figs. 4, 5 and 6 are sections through Fig. 3, as indicated by the lines 4—4, 5—5 and 6—6 respectively.

Referring now to the drawings, and more particularly to Fig. 1, my wringer comprises a body 10 carrying a top 12 and mounted on a head 15 having an operating drive 16 connecting with an ordinary type of washing machine wringer post.

The power head of my wringer is of a type well known in the art and is best shown in Fig. 3. The power connection 16 comprises the downward end of a stub shaft 17 carrying a bevel gear 20. Continually in engagement with the gear 20 are two bevel gears 23 and 24 idly carried on a stub

shaft 25. The inner end of the stub shaft carries a gear 30. Slidably secured to the shaft 25 is a clutch 28 operated by a handle 29 and movable into engagement with either of its adjacent bevel gears, as desired, to establish a drive at the gear 30 which may be either clockwise or counter-clockwise.

Of the three rolls in my wringer, the uppermost one is power driven. Still referring to Fig. 3, this top roll, designated at 35, is carried in a pair of bushings 37 and 38, each of which is secured by respective stirrups 40 against journals 42 integral with the top 12. At the left-hand end of the shaft of the roll 35 (Fig. 3) there is secured a gear 45, the rotation of which revolves the aforementioned roll.

The gears 30 and 45 are operatively connected by an intermediate gear 50. This gear, as shown in Figs. 2, 3 and 4, is carried on a short stub shaft 52 which in turn is mounted in an arm 55 and which is idly carried at the left-hand end of the bushing 37. It will thus be apparent that when the three gears are maintained in operative relation to each other, the roll 35 will be driven by rotation of the connection 16. This means of retaining the member 55 will be hereinafter described.

The roll 35 coacts with a pair of lower rolls 60 and 65. These latter rolls are rotatably carried at their ends by respective bushings 67, which in turn are rotatably carried in roll blocks 70. The bushings are so carried to permit the blocks 70 to rock freely when one pair of bushings are carrying the pressure spring load.

Referring to Fig. 2, it will be seen that the bushings 67 terminate adjacent the rolls in an inner flanged portion, one face of which bears against a cross-rib 71 of the body portion 10. Thus the flared side portions of the two bushings 67 carried on opposite ends of a lower roll shaft prevent axial movement of the rolls by abutting the aforementioned ribs 71. Similarly, sidewise motion of the rolls 60 and 65 is prevented because bushings 67 of the two rolls abut the adjacent inner edges of the ribs 71. As best shown in Fig. 5, the ribs 71 are cut out adjacent their mid-section to permit free up and down motion of the rolls 60 and 65 in the roll blocks 70. The roll blocks 70 are normally prevented from downward movement by the action of a pair of light springs 75 which, at their top, lie in a cup-shaped part of the blocks 70 and at the bottom overlie a pin-shaped projection at the lower edge of the rib 71 (see Fig. 6).

Wringing pressure is applied between the roll

35 and either of the other rolls desired by pressure springs 80, as best shown in Figs. 3 and 5. These springs are restrained between a pivoted block 82 and a top block 85 by bosses on each block and a bolt 88 passing from one block to the other and limiting the expansion of the springs 80. The bolt is so placed that it limits expansion of the blocks but does not prevent compression when clothes are fed to the wringer.

The top portions of the block 85 are peculiarly shaped to permit of their camming under the bushing of either of the lower rolls desired. As shown in Fig. 5, this comprises a pair of recessed cam edges 90 in each block, the right-hand surface being adapted to engage the right-hand bushing 67 and the left-hand surface the left-hand bushing. It will thus be apparent that when the two spring assemblies, as shown in Fig. 3, are moved to underlie the bushing of the roll 60 the same will be urged upwardly against the roll 35 to create a pressure roll bite. The tendency of the roll 60 to move sidewise is prevented by the abutting edges of the ribs 71. At the same time as clothes are fed to the wringer and the rolls tend to separate, the roll 60 may move downwardly by sliding along the ribs 71 and compressing the pair of springs 80. In like manner, when the pressure spring assemblies are shifted to underlie the roll 35 that roll will coact with the top roll to provide a similar intake bite.

The spring mechanism is shifted from side to side by a handle or bail carried in the top 12. This bail comprises a handle member 100 secured at each end to an arm 102 which in turn is pivotally carried by respective bushings 37 and 38. The lower ends of the members 102 carry pins 105, as shown in Figs. 2, 3 and 5. The tops of the blocks 85 are slotted for engagement with the said pins, as also shown in Figs. 2, 3, and 5. At the top of the slot the blocks flare outwardly to provide a surface against which the pins 105 may slide when the top is closed. If the pin and the slots do not coincide, shifting of the handle bar will slide the pins until they drop into their respective slots, at which time the top may be completely closed. It therefore follows that the pressure spring mechanism may be shifted from side to side by rocking the handle 100, which in turn acts through the pins 105 to shift the blocks 85. It should be noted at this time that when the handle is in an upright position the pressure spring mechanism lies between its coacting bushings and there is no wringing pressure applied to either of the lower rolls, which means that there is no wringing pressure between any of the rolls in the wringer. Thus a simple pressure release is effected by shifting the handle 100 to a neutral position.

As heretofore indicated, the top 12 is hinged to the body 40 by a suitable pair of hinges 110. The top is retained in a closed position by any suitable latch as 112, Fig. 6, which acts to draw the top hook portion downwardly as the thumb portion is also pushed downwardly. It should be noted (Fig. 6) that as the top is closed the rolls 60 and 65 are pushed down a small amount by roll 35 against the springs 75 to insure the establishing of an effective auxiliary roll bite.

Referring now to the manner of maintaining a drive between the gears 30, 45 and 50, it will be best to refer to Figs. 4 and 5. Extending lengthwise through the wringer and beyond the outer edges of the lower rolls are a pair of rock shafts 115. At the head end of the shafts there is secured to each a stop plate 117. These plates

5 terminate at their inner ends in cam surfaces which, as shown at the left-hand side in Fig. 4, abut a mating cam surface of the bar 55. The cam end of the plates 117 is limited in upward motion by an abutment 119 adapted to contact the side of the wringer body. When driving the wringer with the pressure mechanism applied to the roll 60 as shown in these drawings, the gear 30 rotates in a counterclockwise direction, Fig. 4. This results in a tendency for it to act against the gear 50 to force the bar 55 to the left and disengage the gears. This motion, however, is prevented by the contacting cam faces of the left-hand plate 117.

Although it is necessary to retain the left-hand plate in position to retain a drive, it is desirable to depress the right-hand plate to prevent driving the wringer in a direction such as will cause the intake bite and the pressure roll bite to coincide. If this were not done the wringer obviously would be unsafe. For this reason mechanism is provided to rock the cam plate which would permit such direction of drive downwardly. Thus if the operator attempts to so connect the drive there is nothing to prevent the gear 30 from rocking the gear 50 and its arm 55 out of engagement with it and thus break any drive to the roll 35. To accomplish the object aforementioned the pivot block 82 adjacent the head is provided with a pair of outwardly extending arms 120 which terminate in pins 122. Secured to the rock shafts 115 are downwardly extending fingers 125 which may be abutted by the pins 122. When the spring mechanism is in the position shown in Fig. 4 the right-hand pin 122 rocks the adjacent finger 125 downwardly, rocking the shaft 115 and dropping the right-hand plate 117 out of coacting position with the block 55. Thus, if the operator attempts to establish a drive in such direction as to make the pressure roll bite the intake bite, the block 55 and the gear 50 slip out of engagement with the gear 30 when the same is rotated and prevent the establishment of the drive.

A pair of springs 127, secured at one end in the top 12 and slidably bearing at the other end in grooves at each side of the block 55, see Fig. 2, tend to maintain the block in a vertical position. Thus if the operator, having once attempted to drive in an incorrect direction, now reverses the drive, the gear 30, due to the inward urging of one of the springs 127, will engage the gear 50 and rock the mechanism into contact with the upstanding cam plate 117 and rotate the roll 35. It will be apparent that when the pressure mechanism is shifted from the roll 60 to the roll 65 the left-hand finger 125 will rock the left-hand cam plate 117 to an inactive position and again safeguard the operator.

60 The cam plate mechanism is so arranged that it is rocked out of engagement with the member 55 when an excess thickness of clothes or the operator's hands are fed to the intake bite. When this contingency arises the auxiliary bite end 65 or left-hand end, as shown in Fig. 4, of the roll blocks 70 drops because of the excessive downward movement of the intake roll 65. The lower edges of the blocks then contact fingers 130 secured to the corresponding rock shaft 115 and thus in turn the cam plate 117 is rocked out of engagement with the bar 55 and the gear 30, due to the direction of rotation, immediately swings the gear 50 out of driving engagement with it. Each shaft 115 carries two fingers 130 so that sufficient depression of either block 70

will stop the wringer. As shown in Fig. 4, the block 70 is permitted some downward movement before it contacts the fingers 130, which actuate the automatic stop.

Feeding of clothes properly through the wringer is insured by guide and stripper construction, as shown in Fig. 6. A guide 135 is positioned to lie between the lower rolls and is supported in the blocks 70 and maintained in position and prevented from rising by locking members 137 held in place by suitable bolts. Thus as clothes are fed past the intake bite they are prevented from passing downwardly between the lower rolls and must pass on through the pressure roll bite. Stripper members 140 are idly secured on the shafts 115 and maintained against the lower rolls by springs 143. Their shape is such that as either of the lower rolls drop away from the upper roll the strippers retain contact with the roll surfaces. Strippers 145 are secured to the top cross-rib, as shown in Fig. 6, and depend downwardly to contact the opposite sides of the roll 35. They are preferably of resilient construction and thus maintain a constant and light contact against the rubber of the roll.

It follows from the foregoing description that I have invented a new and improved clothes wringer in which clothes are fed, first, to an intake roll bite, and then to a pressure roll bite, and that by such construction the operator is protected from injury and the clothes are efficiently wrung. It will be seen that if the operator becomes caught in the wringer, the wringer drive may be immediately stopped and injury prevented, due to the separation between the two rolls of the intake bite.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A three-roll clothes wringer comprising a frame, three rolls carried by said frame whose axes are triangularly spaced apart, one of said rolls being fixed relative to the frame and the other two of said rolls carried in a sub-frame assembly to maintain them in fixed rotating position relative to each other and in simultaneous bite establishing relation with the third roll, resilient means to movably support the sub-frame assembly in the frame, and shiftable resilient means to interchangeably maintain wringing pressure between one of said sub-frame carried rolls and the third roll.

2. A three-roll clothes wringer comprising a top frame, a main frame, a roll carried by said top frame, said frames being fastened together, two rolls carried by said main frame each in bite establishing relation with said top frame roll, resilient means to maintain wringing pressure between said top roll and one of the other rolls, said resilient means being shiftable to establish wringing pressure between the top roll and the third roll, and link members to maintain said two main frame rolls in fixed relative position with respect to each other.

3. A three-roll clothes wringer comprising a main frame and a top frame, said frames being fastened together, three rolls carried by said wringer whose axes are triangularly spaced apart, two of said rolls carried in a sub-frame assembly supported by the main frame to maintain

them in fixed rotating position relative to each other, the third roll carried by said top frame and establishing a clothes bite with each of said other rolls, resilient means to maintain wringing pressure between one of said sub-frame carried rolls and the third roll, said resilient means being shiftable to establish wringing pressure between said other sub-frame carried roll and the top roll.

10 4. A wringer comprising a frame, three rolls carried in said frame in position to establish a pair of roll bites, resilient means shiftable to apply wringing pressure to either roll bite as desired, power means to drive said rolls, reversing mechanism to drive said rolls in either direction desired and mechanism to prevent the rotation of said rolls in such direction as to permit feeding at the pressure roll bite.

20 5. A wringer comprising a frame, three rolls carried in said frame in position to establish a pair of roll bites, resilient means shiftable to apply wringing pressure to either roll bite as desired, power means to drive said rolls, reversing mechanism to drive said rolls in either direction desired and mechanism controlled by the position of said shiftable resilient means to prevent the rotation of said rolls in such direction as to permit feeding at the pressure roll bite.

25 6. A wringer comprising a frame, three rolls carried in said frame and in position to establish a pair of roll bites to feed material through the wringer by passing such material to one roll bite, from the said bite to the second roll bite and then from the wringer, reversing mechanism to reverse the direction of feeding clothes through said wringer, and means to apply wringing pressure to that pair of rolls acting to create the second roll bite and simultaneously prevent the rotation of said rolls in a direction to permit feeding clothes directly to the pressure roll bite.

30 7. A three-roll clothes wringer comprising a frame, rolls carried by said frame and coacting to provide a pair of roll bites and whose axes are triangularly spaced apart, two of said rolls carried in a sub-frame carried by the main frame to maintain them in fixed rotating position relative to each other, resilient means to maintain wringing pressure between one of said sub-frame carried rolls and the third roll, said resilient means being shiftable to establish wringing pressure between said third roll and the other sub-frame carried roll and driving release mechanism adapted to be actuated when a predetermined thickness of material is fed to the wringer to stop the operation of the same.

35 8. In a wringer, a main frame, and a top frame fastened together, a roll carried by the top frame, two rolls substantially vertically movable with respect to said main frame coacting with the top roll to provide a pair of upwardly facing bites, resilient means to urge the lower rolls toward the top roll, wringing pressure mechanism in said wringer including resilient means bearing at one end against said frame and shiftable through three positions, two of said positions respectively establishing wringing pressure at one of said roll bites respectively, and the third position releasing wringing pressure from both said bites.

40 9. In a wringer, a frame, and a top frame therefor, a roll carried by the top frame, two rolls in the frame coacting with the top roll to provide a pair of upwardly facing bites, pressure means to selectively apply pressure at alternate bites, resilient means to urge the lower rolls to-

70 75

ward the top roll and positioning them when the top is open above their position when the top is closed and latch means to retain the top closed and the lower roll unit positioned below the open position by the top roll and against the resilient means.

10. In a wringer, a main frame, and a top frame therefor, a roll carried by the top frame, two rolls substantially vertically movable with respect to said main frame coacting with the top roll to provide a pair of upwardly facing bites, resilient means to urge the lower rolls toward the top roll and positioning them when the top is open above their position when the top is closed and latch means to retain the top closed and the lower roll unit positioned below the open position by means of the top roll and against the resilient means, wringing pressure mechanism in said wringer including resilient means bearing at one end against said frame and shiftable through three positions, two of said positions respectively establishing wringing pressure at each of one of said roll bites respectively, and the third position releasing wringing pressure from both said bites.

11. In a wringer, a frame, three rolls carried thereby in position to establish a pair of roll bites, shiftable pressure mechanism to apply wringing pressure at either roll bite desired, power means to drive said rolls, a separable connection between said power means and said rolls, and mechanism carried by the frame and controlled by the shiftable pressure means to prevent the rotation of said rolls in a direction to permit feeding directly to the pressure roll bite by opening said separable connection.

12. In a wringer, a frame, three rolls carried thereby in position to establish a pair of roll bites, shiftable pressure mechanism to apply wringing pressure at either roll bite desired, power means to drive said rolls, a wringer drive between said means and said rolls comprising a pair of separable drive members, a support for one of said members so arranged and supported as to allow disengagement of the members in either of two directions, the tendency to disengage being caused by the driving engagement of the members, a pair of shiftable cams adapted each to engage said support to prevent disengagement in one of said directions, and means controlled by the position of said pressure mechanism to displace one of said shiftable cams to permit the rotation of said rolls in only one direction for each position of said shiftable pressure mechanism.

13. In a wringer, a frame, three rolls carried thereby in position to establish a pair of roll bites, shiftable pressure mechanism to apply wringing pressure at either roll bite desired, power means to drive said rolls, a wringer drive between said means and said rolls comprising a pair of separable drive members, a support for one of said members so arranged and supported as to allow disengagement of the members in either of two directions, the tendency to disengage being caused by the driving engagement of the members, a pair of shiftable cams adapted each to engage said support to prevent disengagement in one of said directions, and means operated by feeding an excess thickness of clothes to the wringer to shift the active cam maintaining the drive to permit the separable drive members to separate and stop the rotation of the wringer.

14. In a wringer, a frame, three rolls carried

in said frame in position to simultaneously establish two clothes gripping roll bites, mechanism including resilient means to selectively establish wringing pressure at either bite desired, power means to drive said rolls, reversing mechanism to selectively rotate said rolls in either direction desired and mechanism interconnecting said wringing pressure establishing mechanism and said reversing mechanism to prevent operation of said wringer in a manner to allow feeding material directly to the rolls under wringing pressure.

15. In a wringer, a frame, three rolls carried thereby with their axes triangularly spaced apart and with one roll surface in bite establishing relation with the roll surfaces of each of the other two rolls, pressure means to selectively establish an intake light pressure bite and a heavy pressure wringing bite at opposite sides of the wringer, power means to drive said rolls including a separable connection normally tending to disengage under load, reverse means to reverse the direction of rotation of said rolls, and means interconnected with said selective pressure means to actuate said separable connection to prevent feeding clothes directly to the heavy pressure wringing bite.

16. In a wringer, a frame, three rolls carried thereby with their axes triangularly spaced apart and with one roll surface in bite establishing relation with the roll surfaces of each of the other two rolls, pressure means to selectively establish an intake light pressure bite and a heavy pressure wringing bite at opposite sides of the wringer, power means to drive said rolls including a separable connection, reverse means to reverse the direction of rotation of said rolls, said separable connection comprising a driving member, a driven member and an intermediate member therebetween to drivingly connect the driving and driven members, means to normally retain said members in driving engagement and means interconnecting said separable connection and operative upon a predetermined separation between the rolls to release the means for normally retaining said connections, and resilient means acting on said intermediate member to position said member in power transmitting relation with the driving and driven members.

17. In a wringer, a frame, a roll rotatively carried in said frame, a pair of rolls adapted to simultaneously coact with said first roll to provide a pair of clothes gripping roll bites, a pair of roll blocks, one disposed at each end of said wringer and rotatably supporting said pair of rolls in spaced relation with each other, resilient heavy pressure mechanism shiftably supported in said frame and shiftably urged said first roll and either of said pair of rolls toward each other to selectively establish a pressure wringing bite coincident with one of said bites between said first roll and either of said pair of rolls as desired.

18. In a wringer, a frame, a roll rotatably carried in said frame, a pair of rolls adapted to simultaneously coact with said first roll to provide a pair of clothes gripping roll bites, a pair of roll blocks, one disposed at each end of said wringer and rotatably supporting said pair of rolls in spaced relation with each other, resilient light pressure means to urge said blocks and said pair of rolls toward said first roll to establish said bites, resilient heavy pressure mechanism shiftably supported in said frame and shiftable

to urge said first roll and either of said pair of rolls toward each other to selectively establish a pressure wringing bite coincident with one of said bites between said first roll and either of said pair of rolls as desired.

19. In a wringer, a frame, three rolls carried thereby with one roll surface in bite establishing relation with the roll surfaces of each of the other two rolls, means to resiliently lightly press said other two rolls toward said one roll, shiftable mechanism to alternatively establish heavy wringing pressure between said one roll and either of the other two rolls, and link members connecting said other rolls to maintain them in fixed position relative to each other.

20. In a wringer, a frame, three rolls carried thereby with one roll surface in bite establishing relation with the roll surfaces of each of the other two rolls, means to resiliently lightly press each of said other two rolls toward said one roll, shiftable mechanism to alternatively establish heavy wringing pressure between said one roll and either of the other two rolls and link members connecting said other rolls to maintain them in fixed position relative to each other.

21. A wringer comprising a frame, a roll rotatably carried in said frame, a pair of rolls adjacent said first roll, means for alternately pressing one of said adjacent rolls against said first roll to provide wringing rolls, means for pressing the other adjacent roll against one of said wringing rolls to provide rolls for feeding material to said wringing rolls, reversible power means to drive said rolls in either direction and mechanism to prevent the rotation of the rolls acting

as wringing rolls in such direction as to permit feeding material directly to said wringing rolls.

22. A wringer comprising a frame, a roll rotatably carried in said frame, a pair of rolls adjacent said first roll, means for alternately pressing one of said adjacent rolls against said first roll to provide wringing rolls and the other adjacent roll against one of said wringing rolls to provide rolls for feeding material to said wringing rolls, reversible power means to drive said rolls in either direction and mechanism operative to prevent the rotation of the rolls acting as wringing rolls in such direction as to permit feeding material directly to said wringing rolls.

23. A wringer comprising a frame, three rolls carried in said frame in position to establish a pair of roll bites, means shiftable to apply wringing pressure to either roll bite as desired, power means to drive said rolls, reversing mechanism to drive said rolls in either direction desired and mechanism to prevent the rotation of said rolls in such direction as to permit feeding at the pressure roll bite.

24. A wringer comprising a frame, three rolls in said frame with one roll coating with the other two to provide a pair of roll bites, shiftable mechanism to establish wringing pressure at either roll bite desired, reversible power means to drive said rolls and operable in connection with said shiftable mechanism to prevent rotation of said rolls in a direction to permit feeding clothes directly to the rolls under wringing pressure.

CHARLES W. WILLIAMS.
